C. H. IRWIN,
ANGLE PLATE,
APPLICATION FILED OCT. 9, 1914.

1,128,986.

Patented Feb. 16, 1915.

UNITED STATES PATENT OFFICE.

CHARLES H. IRWIN, OF FAIRPORT, IOWA.

ANGLE-PLATE.

1,128,986.

Specification of Letters Patent. Patented Feb. 16, 1915.

Application filed October 9, 1914. Serial No. 365,889.

To all whom it may concern:

Be it known that I, CHARLES H. IRWIN, a citizen of the United States, residing at Fairport, in the county of Muscatine and State of Iowa, have invented certain new and useful Improvements in Angle-Plates, of which the following is a specification.

This invention relates to improvements in splice bars or angle plates designed to secure together rail joints, and its principal object is the provision of a plate of this character which is so cut and bent as to form coöperating rail and tie-engaging flanges arranged with respect to each other so as to obtain a most rigid connection for preventing spreading or turning of the rails. This and such other objects as may hereinafter appear are attained by the novel construction, combination and arrangement of parts to be herein- 20 after specifically described and claimed.

Reference will now be had to the accompanying drawings forming a part of this specification, wherein:—

Figure 1 is a perspective view showing the application of my invention to a rail joint; Fig. 2 is a horizontal sectional view on the plane indicated by the line 2—2 of Fig. 1; and Fig. 3 is a plan view of a blank from which my angle plate is formed.

Specifically describing the invention, the numeral 1 designates an angle plate which constitutes the subject matter of my invention and comprises a body portion having its longitudinal edge portion bent upwardly to form a flange 2 adapted to be disposed against the web of a rail. At the opposite side the body portion of the plate is formed with a lateral extension 3 and this extension, as will be observed by reference to Fig. 1, is cut or formed with an L-shaped slit 1^a and the material at the end of this slit is bent downwardly as clearly shown in Fig. 1 so as to form a rail engaging flange 4 particularly engaging beneath the base of the rail. The material at the side portion of the L-shaped slit is also bent downwardly to form a tie-engaging flange 5 which is at right angles to the flange 4, the latter being in alinement with the rail. It will be noted from the drawings that the opposite side of the body portion and lateral extension 3 of the plate 1 is similarly formed with these

flanges designated 4', 5', and a plate thus formed is disposed at each side of a rail joint, the rails being designated in the drawings by the characters A—A. The plate is formed with suitable openings to admit of the fastening members or bolts 6 extending through the extension 3 and the bolts 7, 7' passing through the flange 2 and the web 60 portions of the rails A—A.

I preferably employ in conjunction with the angle plate hereinbefore described the metallic cross bar or tie element 8 upon which the rails are seated and this member 65 may be disposed and properly secured in any desired manner to an ordinary tie, or where desired constitute the tie itself. In employing the particular angle plates arranged at opposite sides of the rails and secured to the 70 rigid member 8 a very rigid construction is secured which tends to prevent the turning of the rail members or likelihood of their spreading. The plates are, of course, made of metal and of a suitable thickness to withstand the ordinary strains placed upon these members and it will be obvious that the angular arrangement of the rail and tie engaging flanges maintains a proper engagement and disposition of the plates and 80 the rails with respect to the tie members upon which they rest.

Having thus described the invention, what is claimed as new is:—

1. An angle plate of the class described 85 comprising a body portion having an L-shaped slit formed therein, said body portion having a lateral extension, the material at one side of the slit being bent downwardly to form a tie engaging flange and at the end of the slit similarly bent to form a rail engaging flange at right angles to the tie engaging flange and parallel with the rail.

2. An angle plate of the class described 95 comprising a body portion having a lateral extension, the extension being formed with an L-shaped slit at each side thereof, the material at one side of each slit being bent downwardly to form tie engaging flanges at 100 opposite sides of the extension, said material being also bent in a similar manner at the end of each slit to form rail engaging flanges arranged at opposite sides of the tie at angles

to the tie engaging flanges and parallel with the rail beneath which they engage, and said body portion being also formed with an upstanding flange adapted to rest against the 5 web of a rail, and web and tie fastening members passing through the upstanding flange and the lateral extension.

In testimony whereof I affix my signature in presence of two witnesses.

CHARLES H. IRWIN.

Witnesses:

GUSTAVUS ALDEE,
H. C. HANEY.
